UNITED STATES PATENT OFFICE

2,110,659

AUTOMATIC FIRE EXTINGUISHER
SPRINKLER

Harry D. Cooper, Poughkeepsie, N. Y.

Application July 22, 1936, Serial No. 91,937

1 Claim. (Cl. 169—26)

This invention relates primarily to a fire extinguisher, and more particularly to an individual type of extinguisher which is intended to be mounted within a room, and which is automatic in its action.

The principle involved is that of the well-known sprinkler system whereby the water or liquid is automatically released by a fuse that is melted by the heat of the fire, but such systems are expensive to install and are intended for large buildings.

There have also been made individual extinguishers of the soda-acid type which are hung up when not in use, and when a fire occurs, are taken down and inverted, whereby upon the acid and soda being mixed, a gas pressure is generated and the mixture directed upon the fire, but such devices are not automatic in their action and require manual operation.

20 The object of the invention is to provide an individual automatic fire extinguisher that is simple in construction durable, efficient, and fully automatic in its action.

Another object of the invention is to provide a 25 device of this class that may be mounted in a room and which will upon the melting of a fuse distribute the chemical over a large area of the entire room in the form of a spray or gas, depending upon the nature of the fire extinguishing chemicals employed in the device.

Another object of the invention is to provide a 30 device of this class that may be used with either a liquid or a compressed gas.

Another object of the invention is to provide a 35 device of this class that may be readily and quickly reloaded after it has been used.

With these and other objects in view, my invention consists in certain novel construction and combination of parts as will hereinafter be fully 40 described and claimed and further illustrated in the accompanying drawing which forms a part hereof, and in which like figures of reference refer to corresponding parts in all of the views, and it is understood that slight changes may be 45 made without departing from the spirit of the invention.

In the drawing:

Figure 1 is a side elevation of the device, shown 50 in a non-operative position.

Figure 2 is a front elevation of the same.

Figure 3 is a view similar to Figure 1, but shows the device in an operative position, after the fusible link has been melted.

55 Figure 4 is an enlarged vertical sectional view

of the chemical container showing the detailed construction and arrangement of the parts.

Figure 5 is a partial detail view showing the operation of the valve.

Figure 6 is an enlarged sectional view taken on 5 the line 6—6 of Figure 2, showing the spring for rotating the container.

Figure 7 is an enlarged sectional view taken on the line 7—7 of Figure 2, showing one of the bracket arms, bearings, and the spring. 10

Referring to the drawing:

The device comprises a mounting bracket 10 designed to be attached to a wall, post, or ceiling of a room, and is formed with two supporting arms 11 and 12, the other ends of which terminate in the split rings 13 which are contracted by the bolts 14. 15

Within these rings 13 are clamped the bearing blocks 15 and 16 having the ball bearings 17. The bearing block 15 is formed with a drum 18 within which is mounted a flat spiral spring 19 having one end secured to said drum 18 as at 20, and the other end to a collar 21 as at 22; said collar 21 being secured by a key 23 to the shaft 24 in such a manner that the collar 21 rotates 25 with the shaft 24 while the drum 18 is held rigid by the bearing block 15. 20

The chemical container 25 may be of any desired shape and size and is provided with the aligned trunnions 26 and 27 by which it is rotatably mounted in one of the bearings 17; the trunnion 26 having the end slotted as at 28 by which it is secured to the tongued end 29 of the shaft 24 in such a manner that by removing the block 15 from the ring 13, the container may be 30 removed from the bracket if desired or the spring 35 wound up.

The discharge end of the chemical container 25 is provided with a discharge pipe 30 extending into the container 25 and communicating with a holder 31 designed to contain either the usual acid bottle or a compressed gas capsule, and to the lower end of the pipe 30 is freely rotatably secured a spinner 32 mounted on an adjustable pivot pin 33 threaded into a cage 34 attached to 40 the container in such a manner that the liquid or gas vapor escaping through the pipe 30 will contact with, rotate, and be discharged over a large area by the spinner 32. 45

The filler end of the container 25 is formed 50 with a neck 35 threaded for a closure cap 36 within which is slidably mounted a pin or plunger 37 formed with a point 38 by which the gas capsule in the holder 31 may be pierced to allow the gas to escape; the plunger 37 being normally re- 55

tained in an outwardly extended position by a spring 39 located in the gland 40 which is threaded into the cap 36, but should the usual acid bottle be used, this plunger will not be required.

5 As shown in Figure 1, the chemical container 25 is normally held in the bracket 10 in a non-operative position; that is, with the filler end up and the discharge end down, and is retained in this position by a dog 41 which is rigidly secured 10 to the outer end of the shaft 24, and the rotation of the container 25 is limited to 180 degrees by a stop 42 secured to the drum 18.

The container 25 is rotated against the pressure of the spring 19 into the position shown in 15 Figure 1, and the dog 41 is engaged by the lower end of a latch 43 pivoted as at 44 to the ring 13; the upper end of this latch 43 being bifurcated as at 45 and engaging an annular groove 46 in a link 47 of fusible material which is renewably 20 and adjustably mounted in a clamp 48 extending upward from the arm 11 by a set screw 50.

It will be readily seen, that the container 25 having been charged with soda water and an acid bottle placed in the holder 31 and held in the 25 non-operative position shown in Figure 1 with the latch 43 engaging with the dog 41 to retain the container 25 from rotation as urged by the spring 19 and the latch 43 being held by the head of the link 47, then when said head or any part 30 of the link 47 fuses or melts due to the rise in temperature caused by a fire, the latch 43 will be released and in turn release the dog 41 and allow the container 25 to be rotated and reversed, mixing the acid with the soda and creating a pres-

sure to expel the chemical through the spinner 32.

Should a compressed gas capsule be used and mounted in the holder 31 an anvil 49 is mounted on the bracket 10 in the path of the plunger 37 5 as the container rotates, striking the end of the plunger 37 and forcing its pointed inner end to puncture the gas capsule allowing the gas to escape into the container 25 and out through the pipe 30 and spinner 32.

10 Having thus described my invention, what I claim is new and desire to secure by Letters Patent, is:

In an automatic fire extinguisher of the class described comprising a mounting bracket formed 15 with two arms provided with bearings in the ends thereof, a fire extinguishing medium container provided with aligned trunnions rotatably mounted in said bearings, a spring for urging the rotation of said container in one direction only, 20 and a stop for limiting said rotation, a heat-fusible latch for retaining said container in a normally non-operative position, and by the fusing of said latch allowing the container to rotate as urged by said spring and limited by said stop, 25 a capsule containing compressed gas mounted in said container, a sprayer member mounted on said container, a plunger mounted in said container in axial relation to the sprayer, and means mounted on the bracket in the path of the plunger for causing it to puncture the capsule as the container rotates to discharge the extinguishing medium through the sprayer.
